The ornamental design for a bottle, as shown and described.

DESCRIPTION

FIG. 1 is a front elevational view of a bottle embodying our new design, the rear elevational view being the same in appearance;

FIG. 2 is a right side elevational view of the bottle, the left side elevational view being the same in appearance;

FIG. 3 is a top plan view thereof;

FIG. 4 is a bottom plan view thereof; and,

FIG. 5 is a fragmentary cross sectional view taken along line 5—5 in FIG. 3.
